UNITED STATES PATENT OFFICE.

SQUIRE TONEY, OF VIROQUA, WISCONSIN, ASSIGNOR OF ONE-FOURTH TO JOHN DEVLIN, OF VIROQUA, WISCONSIN.

WASHING-MACHINE.

No. 895,059.

Specification of Letters Patent.

Patented Aug. 4, 1908.

Application filed August 20, 1907. Serial No. 389,421.

To all whom it may concern:

Be it known that I, SQUIRE TONEY, a citizen of the United States, residing at Viroqua, in the county of Vernon and State of Wisconsin, have invented certain new and useful Improvements in Washing-Machines; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to washing machines, of the reciprocating-rubber type.

It has for its object to form a machine having certain features of construction herein-after particularly specified whereby the 20 clothes to be washed will be subjected to a rubbing action on all sides, and in which the possibility of the clothes becoming tangled and torn is avoided, and in which the rubbing frames can be readily adjusted to conform to the conditions to be met according as 25 a larger or smaller number of articles are to be washed.

To the accomplishment of the foregoing and such other objects as may be made hereinafter to appear the invention consists in the features hereinafter particularly described and then sought to be defined by the claims, reference being had to the accompanying drawings forming a part hereof and in which 30

35 Figure 1 is a plan view of the machine; Fig. 2 a vertical longitudinal section; Fig. 3 a cross section on the line 3—3 of Fig. 1; Fig. 4 a perspective of the upper roller frame, and a portion of one of the end boards; and Fig. 5 a 40 detail view, partly in section, of the oscillating lever.

In the drawing, the numeral 1 designates a box of suitable shape and dimensions, supported upon suitable legs 2 and having a 45 cover or top 3 which may have handles 4 for lifting it from place, or which may be otherwise made so as to permit access to the interior of the tub. In the bottom of the tub is placed a frame composed of side members 5 connected together by corrugated rollers 6 50 suitably spaced apart and having their tops substantially flush or in the same plane with the top surfaces of the side members, said top surfaces being corrugated as shown at a 55 so that they together with the corrugated

rollers 6 form a corrugated surface for the support of the articles to be washed. The rollers 6 are above the bottom of the tub so that a space will exist between the rollers and beneath the corrugated bottom to receive the sediment or dirt that settles in the bottom beneath the clothes or other articles being washed.

The sides of the tub are corrugated as shown at b, in any suitable manner and for a suitable height so as to present corrugated sides for the clothes to be rubbed against.

Above the lower frame there is placed a second frame somewhat shorter than the bottom frame and formed of side members 7 whose lower edges are corrugated as shown at c, and corrugated rollers 8 connecting the side members. The side members 7 beyond the end rollers are formed with dovetail tongues to fit in correspondingly shaped grooves or ways 9 in the guide end boards 10 whose inner faces are corrugated transversely as shown at d. These end boards prevent the clothes which lie between the upper and lower frames from passing beyond the ends of the 75 frames and packing or tangling between the ends of the frames and the ends of the box, in the reciprocation of the upper frame.

The end boards 10 and the frame which carries them are vertically adjustable one 80 relatively to the other, that is, if the frame be raised so as to carry with it the boards the set screws 11 may be loosened so that the end-boards may be lowered to bring them to the plane of the lower frame and then the set screws tightened to hold the boards in that position. Or the set screws may be first loosened and the frame raised without raising the end-boards and then the set screws tightened so as to hold the end boards to the 85 frame. In either case, one of the parts, that is the frame and the end boards carried by it are adjustable one relatively to the other according to the number or quantity of pieces of wearing apparel or other articles being washed that may be placed between the upper and the lower sets of rubbing surfaces.

The top rubber or frame is held down to its working position by adjustable boards 13 90 slide in dovetailed ways 14 formed in the sides of the tub and held to their adjustment by set screws 15, or otherwise. The lower edges of these boards bear against anti-friction rollers 16 journaled in castings 17 suitably secured to the top edges of the side 95 110

members 7 so that the top rubber or frame will be smoothly guided in its reciprocation and be firmly held to its working position.

The top rubber or frame is reciprocated by means of a pitman 18 attached to the top rubber at one end preferably by a dovetailed head 19 fitting in a vertical dovetailed groove 20 formed in a bracket 21 supported on the diagonal bracing bars 22, thus permitting the top frame or rubber to be raised or lowered without throwing the pitman out of operative position. This pitman passes through an opening 23 in one of the end boards 10 and through the end of the tub where it is connected to a lever 24 pivoted to a bracket 25, the opposite end of said lever being connected to a crank pin 26 the shaft of which passes through a boxing 27 formed as a part of a casting 28 and carries at its end a sprocket wheel 29 to which motion is transmitted by a chain 30 which passes around a sprocket wheel 31 mounted on the casting 28 and operated by a crank handle 32. By means of the driving mechanism described the top frame or rubber is reciprocated back and forth, causing the articles between the top and bottom frames to be rubbed by the corrugated rollers of the top and bottom frames as well as by the corrugated edges of the side members of the two frames, and also by the corrugated sides and the corrugated end boards, the clothes being given at the same time a back and forth movement, to a greater or less extent, between the two frames. It will thus be seen that corrugated rubbing surfaces are presented to the clothes on all sides so that they are thoroughly rubbed and cleansed. It will also be observed that the frames are adjustable to increase or lessen the space between them so as to conform to the bulk of the clothes being washed, and further that the danger of tangling and tearing the clothes by getting between the end rollers of the frames and the ends of the tub is prevented by the adjustable end boards. It will also be observed that the dirt washed from the clothes will settle in the bottom of the tub below the bottom frame instead of being carried back and forth through the clothes.

The bottom and top rubbing frames can be readily removed by taking out the adjustable side boards 13 and lifting them out of the tub.

To facilitate this being done without dismembering the driving gears, the pitman 18 may be made in two parts, one part being formed with a socket 33 and the other part with a pintle 34 to fit in the socket and be held therein by a cotter-pin 35, which permits the parts of the pitman to be separated and one part removed with the rubbers or roller frames when the latter are to be taken out.

It is obvious that changes can be made in some of the parts without affecting other parts, and while I have described the preferred construction of each part changes can be made in the parts and still be embraced within the scope of the invention as defined by the claims.

Having described my invention and set forth its merits, what I claim is:

1. In a washing machine, the combination with the lower rubbing frame having rollers, of the upper reciprocating adjustable rubbing frame having rollers, adjustable side boards bearing upon the upper frame and restricting its vertical movement, and end boards carried by the reciprocating frame, said end boards and frame being adjustable one relatively to the other, substantially as described.

2. In a washing machine, the combination with the lower rubbing frame, of the upper adjustable reciprocating rubbing frame, a vertically grooved bracket carried by the upper frame, and a driving pitman having its head working in the vertical groove of said bracket, substantially as described.

3. A washing machine comprising a tub having its side walls corrugated vertically, a frame in the bottom of the tub provided with corrugated rollers, a reciprocating frame having corrugated rollers and located above the lower roller frame, end boards carried by the upper frame and having corrugated faces, said frame and end boards being adjustable one relatively to the other, and means for reciprocating the upper frame, substantially as described.

In testimony whereof I affix my signature in presence of two witnesses.

SQUIRE TONEY.
